Primary Examiner — Ian Simmons*Assistant Examiner* — Rashida C McCoy(74) *Attorney, Agent, or Firm* — Williams Intellectual Property; Benjamin F. Williams(57) **CLAIM**

The ornamental design for an infant one-piece clothing article, as shown and described.

DESCRIPTION

FIG. 1 is an enlarged partial rear view of an infant one-piece clothing article, showing my new design;

FIG. 2 is a rear view of an infant one-piece clothing article; FIG. 3 is an isometric rear view thereof, in used condition; and,

FIG. 4 is an isometric front view thereof, in used condition. The broken lines in the drawings represent environmental subject matter that form no part of the claim.
